UNITED STATES PATENT OFFICE.

HUGH McCAGHREN, OF OTTAWA, ONTARIO, CANADA.

TICKET HOLDER.

Application filed October 15, 1923, Serial No. 668,612. Renewed March 30, 1925.

To all whom it may concern:

Be it known that I, HUGH McCAGHREN, a citizen of the Dominion of Canada, and resident of Ottawa, in the county of Carleton 5 and Province of Ontario, Dominion of Canada, have invented certain new and useful Improvements in Ticket Holders, of which the following is a specification.

This invention has relation to certain new 10 and useful improvements in a ticket holder and has for its primary object the provision of a holder in which a number of strips of tickets may be carried and the strips ejected one at a time without disturbing 15 the remaining strips.

The invention has for another object the provision of a ticket holder of the character stated in which is employed a resilient ticket support which resiliently retains the tickets 20 in proper position with the uppermost tickets supports thereon projected toward the exit slot which permits only one strip at a time to be ejected from the holder.

The invention has for a further object 25 the provision of a ticket holder of the character stated which is of simple construction, inexpensive to manufacture and may be readily supported on a belt or the like with the resilient ticket supporters removably held in place in the ticket compartments for which they are provided.

A still further object of the invention resides in the provision of a ticket holder of the character stated which is composed of 35 the minimum number of parts of simple construction and arrangement and in which the resilient ticket support is constructed in different sizes to accommodate the different strips of tickets as employed by the 40 street car companies or the like, each resilient ticket support being formed so as to press the strips of tickets against one wall of the pocket in which they are positioned and force all of the strips in one direction 45 with the ends overlapping in one direction toward the exit opening, thereby automatically feeding the strips in succession to the outlet opening or slot through which they may be ejected one at a time.

With the foregoing and other objects in 50 view as will appear as the description proceeds, the invention consists in the novel construction, combination and arrangement of co-operating elements as hereinafter more 55 specifically set forth, claimed and shown in

the accompanying drawings, forming a part of the present application, in which:—

Fig. 1 is an elevation of the ticket holder.

Fig. 2 is a side elevation, at right angles to Fig. 1.

Fig. 3 is a bottom plan view.

Fig. 4 is a longitudinal section, substantially on the plane of line 4—4 of Fig. 1, looking in the direction indicated by the arrows.

Fig. 5 is a detail perspective of one of the resilient ticket supports, removed.

Fig. 6 is a perspective view of a modified form of the invention.

Referring more in detail to the drawings in which similar reference characters designate corresponding parts throughout the several views, it will be noted that the body 10 is of rectangular form in elevation, plan and section and is composed of one section of material with the ends of the body open. A top plate 11 is employed for closing the upper end of the body 10 and leaving only a narrow discharge slot 12 along one longitudinal edge of the top plate 11, whereby 70 the strips of tickets may be readily ejected, the slot 12 being of proper size to permit the discharge of only one strip of tickets at a time. The body 10 is divided into two compartments by a central longitudinal partition wall 13, which is shown as being 75 formed by turning inwardly at a right angle one longitudinal edge of the material from which the body 10 is formed, while the other edge is extended straight across the rear side of the body to a point past the partition wall 13. This may be readily understood by referring to Fig. 3 of the drawings. It may also be seen from Figs. 2, 3 and 4 that an elongated loop 14 is provided 80 on the rear wall of the body 10 and extended longitudinally thereof, whereby the device may be readily supported on a belt or the like passed through the loop 14. This 85 loop 14 is shown as being formed of a section of material bent upon itself with one end 15 of the material bent around and over the other end 16, which latter is turned back upon itself. This provides a tongue 17 90 which serves to lock the loop 14 on the belt or other member extended through the loop 14.

For each compartment or pocket in the body 10, an elongated longitudinal slot 18 is provided in the front wall of the body 10. 110

Removably positioned in each compartment or pocket is a resilient support 19 which is in the form of a spring material strip bent transversely upon itself intermediate its ends 5 to provide the lower flat finger 20 and the inclined upper finger 21, having its front end 22 curved upwardly slightly, as shown in Figs. 4 and 5. The central portion of the support 19 is bent upon itself to form a heel 23 which fits snugly in the lower end of the compartment or pocket and has an inclined forward wall 24 against which one end of the strips of tickets engage when resting on the inclined upper fingers 21 of the support 19. The support 19 is readily inserted 10 or removed from the lower end of the compartment or pocket for which it is provided and when in position presses the strips of tickets toward the outer slotted wall of the 15 compartment or pocket with the ends of the tickets overlapping, so as to present the uppermost or outermost strip to the discharge slot 12. A locking ridge 25 is provided transversely of the lower flat finger 20 of the support 19 by pressing upwardly 20 a portion of the same for engagement with the locking rib 26 provided on the corresponding wall of the compartment or pocket and extended transversely thereof. This 25 may be readily understood from Figs. 4 and 5. The strips of tickets may be seen in Figs. 1 to 4 inclusive and are designated by the numeral 27. It is also to be understood that the strips 27 are forced outwardly by 30 inserting a finger or thumb in the longitudinal slot 18 of the pocket, pressing on the strips and moving the same longitudinally in the pocket toward the discharge opening 12. It is to be further noted that the ridge 35 25 grips the rib 26 sufficiently to retain the support 19 in proper position within the compartment or pocket, but will permit releasing thereof when it is desired to force the support 19 out of the compartment or 40 pocket for placing thereon a new supply of strips or substituting a different holder with 45 other strips of tickets.

In Fig. 6 a modified form of the invention 50 is disclosed, showing a ticket holder of one compartment or pocket only for single tickets. This modified form includes a body 28 formed of a single section of material with the ends of the body open. An end plate 29 is extended across one end of the body 28 to close the same and leave only a 55 sufficient open space to provide a discharge slot 30 for the tickets 31. An elongated longitudinal slot 32 is provided in the upper face of the body 28 so that the tickets 31 60 may be readily forced out of the holder by way of the discharge slot 31 in the same manner as in the preferred form of the invention. A ticket support 33 is removably inserted from the other end of the body 28 65 and corresponds to the form of ticket sup-

port 19 disclosed in the preferred form of the invention and, therefore, needs no further detail description.

It is believed the complete construction and operation of the invention may now be 70 apparent from the foregoing paragraphs, taken in connection with the accompanying drawings without further detail description. It may be briefly stated, however, that the preferred form is designed particularly for 75 conductors of street cars, where several different types of tickets are employed. The modified form is designed as a vest pocket ticket holder for individual use and may be readily carried in a pocket, handbag or the 80 like. The strips of tickets may be readily inserted or removed from the holder in the two different forms and either form of holder may be readily refilled as required.

While the preferred embodiment of the 85 invention has been disclosed, it is to be understood that minor changes in the details of construction, combination and arrangement of cooperating elements may be resorted to within the scope of what is claimed 90 without departing from the spirit of the invention.

What I claim as new is:

1. A ticket holder including a body having an open end and a discharge slot at its 95 other end; a resilient ticket support held in said body and including an inclined finger portion serving to support tickets in overlapped relation with the uppermost ticket presented to the discharge slot; said support including a heel carrying an inclined face for forcing the tickets to overlapping position; means for retaining said support in normal position within said body; said body having a slot formed in one face for 100 exposing the uppermost ticket and permitting discharging of the same through said discharge slot by pressure on the ticket and movement of the same longitudinally in said body; and means carried by said body for 105 supporting the same on a belt.

2. A ticket holder including a one piece body with a portion of the material thereof turned to form a longitudinal partition within the body, dividing the same into compartments; an end plate for closing one end of the body and leaving a discharge slot at the end of each compartment; said body having slots in one wall of the compartment; a spring ticket support for each compartment; each spring ticket support being bent upon itself intermediate its ends to form a flat finger and an inclined finger having its free end curved; the central portion of the spring ticket support being bent to form a heel with an inclined face for engagement with one end of the ticket resting on the inclined finger, whereby the heel and the inclined finger cooperate to resiliently retain the tickets in overlapped position and with 110 115 120 125 130

the uppermost ticket engaged with the slotted wall of the compartment, thus permitting the uppermost ticket to be readily discharged through the slot by means of a finger inserted in said slotted wall and engaged with the uppermost ticket; means carried by another wall of the compartment and by the flat finger of the resilient ticket

support to normally retain said resilient ticket support in position within said compartment; and means carried by the ticket holder for mounting the same on the supporting member.

In testimony whereof, I affix my signature.

HUGH McCAGHREN.
